REINFORCED CAP

Frank K. Lipschutz and Samuel Rosenberg, Louisville, Ky.

Application May 28, 1954, Serial No. 433,010

7 Claims. (Cl. 2—195)

The present invention relates to a reinforced cap of 15 the type in use by the armed forces, and to the reinforcing structure thereof.

The construction of such caps comprises generally a pliable headband, united along the top to form a crest and front and rear prows. In one modification, the 20 headband is united directly to form a single crest, and in another modification the headband is united by a pleated gore to form a double crest. An ornamental covering band may be united to the headband along the bottom edge, and a sweatband may be sewed to the interior of the head band adjacent the bottom. When this type of cap is worn the headband is distended to receive the head and this ordinarily causes the crest to sag and the prows to collapse or develop a break, thus destroying the neat trim appearance of the cap.

It is an object of the present invention to provide an overseas type of cap which maintains a smoothly curved outline at the crest, and which prevents a break or collapse developing at the prows of the cap when the cap is worn.

Another object is the provision of a reinforcement for an overseas cap which preserves the overall trim appearance of the cap, and which is held in place by the sweat band, thus rendering the reinforcement easily removable and eliminating the need to sew or otherwise 40 secure the reinforcement into the cap.

The invention will be described in detail in the following specification taken in connection with the accompanying drawing illustrating preferred embodiments by way of example, and wherein:

Figure 1 is a side elevation of one form of cap to which the invention is to be applied;

Figure 2 is a longitudinal cross sectional view of another form of cap having the invention applied thereto;

Figure 3 is a perspective view of the cap shown in Figure 1 with parts cut away to show the operation of the invention;

Figure 4 is a side elevation of a modified form of the invention;

Figure 5 is an end view of the prop shown in Figure 3 as viewed from the right;

Figure 6 is an elevational view of a further modification;

Figure 7 is a side elevation of another modification;

Figure 8 is a cross sectional view of the cap showing a further modification applied thereto;

Figure 9 is a side elevation of the prop illustrated in Figure 8; and

Figure 10 shows the cap worn with and without a prop.

Referring to the drawing, Figures 1 and 3, there is shown one type of cap comprising a pliable headband 1 with a pleated gore 2 uniting the top edge of the headband to form crests 3 and 4 and front and rear prows 5 and 6. An ornamental band 7 extends around the outside of the cap, and a sweatband 8 is provided around the inside of the cap as shown in Figure 2. In Figure 2 we illustrate in cross section a type of cap made by

2

directly uniting the top edge of the headband to form a single crest 3a. As the details of the seams, lining and other structure of the caps are not part of the present invention there is no attempt made to depict or describe them, except insofar as necessary to an understanding of the invention.

When the cap is worn it is intended that the crests 3 and 4 (3a in Fig. 2) be maintained erect in proper curvature, and the prow lines remain unbroken. However, referring to Figure 10 it will be seen that upon distending or opening the headband to place it on the head the rounding of the headband to conform to the outline of the head causes a break in the front or rear prows, or both, with formation of protruding beaks 10 and 11, and the pull of the headband at the top where the edges are united flattens the crest as shown. This appearance of the cap is undesirable. We have observed that a reinforcement solely of the crest of the cap will prevent collapse of the crest, but serves to accentuate the front and rear beaks of the cap.

The construction by which this undesired deformation of the cap is avoided now will be described with relation to a single crest cap. Referring to Figure 2, we provide a prop in the form of a wire having a chine portion 13 and bent at 15 to provide a leg 16. The prop is inserted into the cap with its end 17 at the top point 18 of the front prow 5, and the end 19 of leg 16 in the sweatband 8 at the rear prow 6. The leg 16 may be substantially the height of the rear prow so that the bend 15 is positioned substantially at the top point 21 of the rear prow. The prop preferably is made of a springy wire and the chine portion is bowed to conform substantially to the crest line of the cap. Thus, the resiliency of the prop member maintains the end 17 at the top point 18 and the leg 16 at the rear prow, and holds the prop member in the cap. However, if desired, the chine may be performed to the curve of the crest and the end 17 held at the point 18 in any suitable manner. No additional fastening means for the prop is required so that, the prop is easily removed when the cap is to be cleaned or laundered, and is then easily replaced.

When the headband is distended on the head of the wearer, the collapse of the crest is prevented by the chine portion 13, and the formation of a beak or horn at the rear prow is prevented because leg 16 prevents collapse of the prow. The provision of a leg at the front prow is not necessary in some cases because there appears to be less tension at the front prow of the cap when it is worn. Also, as the ornamental band is of double thickness at the front, this may also help to support the front prow and prevent its collapse.

However, where desired, a modified prop may be provided to support both the front and rear prows. As shown in Figure 4, the prop is bent at 15 to provide the leg 16, and is bent at 22 to provide a front leg 23, terminating at 24, the portion between the bends providing the chine 13c. As the front prow of the cap is usually of lesser height than the rear prow, the front leg 23 may be made correspondingly shorter than the rear leg. Also, it is preferred to have the legs 16, 23 extend in diverging relation to the chine portion so that when the ends of the legs are pushed together in placing them in the sweatband of the cap the chine is bowed and its span or chord is shortened to conform substantially to the crest of the cap, as shown in dot and dash lines in Figure 4.

The construction shown in Figure 4 supports the single crest and prevents a break occurring at both the front and rear prows, and thus in wearing the cap it is not necessary to carefully adjust the cap to prevent its collapse at any point. This is of advantage because, the cap can be worn high on the head or low on the head as desired, without

the need to adjust the cap to prevent breaks in its contour.

It should be pointed out that when the prop shown in Figure 4 is inserted in the cap, it is the contraction of the ends 19, 24 which bow the chine, and the bends 15, 22 need not lie snugly in the points 21, 18 of the cap. In other words, there is no tensioning or strain of the cloth at the peaks or brows of the cap. Because of the confluence of cloth at these points of the cap there is enough stiffness in the cap itself to maintain the points in proper position, as long as no break is allowed to occur in the crest or brow lines of the cap. It is not necessary that the chine and legs tension the cloth of the cap, but they merely provide a support to prevent tension in the cap from collapsing the crest or brows.

In Figure 3 we show a modification designed for use with a double crest cap. This modification employs double wires, each comprising a chine portion 13a and a pair of legs 16' and 23''. As shown the free ends of the legs are fastened together by a lug 25 but they may be united in any other suitable manner, or the entire double prop may be made from a single continuous length of wire. In use, this prop is inserted in the cap with the lugs 25 on the ends 19' and 24a received in the sweatband at the rear and front brows respectively and with a chine 13a in each crest 3, 4 of the cap, the pleat 2 being received between the chines. When the headband is distended in placing the cap on the head the tension of the headband opens the gore and separates the crests somewhat at the middle and the chines separate as required to support the crests in separated position, so that the chines are each bowed in a vertical plane to conform to the respective crest lines and are bowed relatively horizontally to conform to the separation of the crest lines. At the brows little separation of the chines occurs. The legs prevent a break or pucker at the brows so that the cap presents a neat trim appearance when worn, free of pucks or wrinkles, with the crests smoothly curved, and the brows unbroken.

It should be pointed out that here too it is not necessary for the bends 15a and 22a to fit snugly into the points 21 and 18 of the cap, nor is it necessary that the prop maintain the crest or brows under tension when the prop is inserted into the cap. In wearing the cap the headband conforms more or less to the circular contour of the head, and as the distension of the headband is greatest at the middle the tendency is for the crest to collapse at the middle, the gore opens to allow shifting of the crest to relieve the tension and avoid wrinkling, and the chines support the crests in any position they may assume. At the front and rear brows the tension in the headband will tend to collapse the brow lines to produce horns, but the legs provide supports along the height of the brows and prevent their collapse. Consequently, the merger of the circular form of the headband with the elongated crest occurs substantially along lines radiating from the front and rear top points 18, 21 as shown by the dot and dash representation and shaded lines in Figure 10.

In the modification illustrated in Figure 6, two separate prop members are employed. One prop comprises a chine portion 13 having a leg 16 at one end, the other end of the chine being bent at 17, as previously described in connection with Figure 2, and the other prop comprises a chine portion 13' having a leg 23' at one end, the other end being bent as above described, the bent end being indicated at 17'. In use with a single crest cap, one prop is inserted in the cap with the end 17 disposed at the front point 18 of the cap and the leg 16 at the rear brow 6, the end 19 being received in the sweatband as shown in Figure 2, and the other prop is inserted in the cap with the end 17' disposed at the rear point 21 of the cap and the leg 23' at the front brow 5, the end 24' being received in the sweatband. Thus, in applying this modification to the cap shown in Figure 2 (without a gore) the chines 13, 13' lie along the crest and each prop is held

in position by the bowing of its chine. However, in applying this modification to a gore type cap shown in Figure 3, each chine will lie along its respective crest 3, 4, with the pleat 2 lying between the chines. This modification has the advantages that it is somewhat easier to insert into the cap, and the ends 17, 17' can lie exactly in the points of the cap, and has the disadvantage that unless carefully made it may not keep the two crest lines of the cap in exact conformity.

In the modification shown in Figure 7, the wire is bent substantially at a right angle at its ends to provide a chine portion 13d and ends 16a and 23a which are bent or kinked outwardly at 16b and 23b, so that the legs 16, 23 are formed of two angularly disposed portions. This 15 is shown in dot and dash lines. When the legs are contracted in the cap, as shown in full lines, acute bends 15 and 22 are formed which better fill the points 21, 18 of the cap. Here also it should be understood that it is the contraction of the ends 19 and 24 which bows the 20 chine, and that the chine does not necessarily apply tension to the crest, nor do the bends 15, 22 necessarily fit snugly into the corners 21, 18 of the cap when the prop is assembled into the cap. Thus, the chine 13d can be made shorter than the curved crest line, if desired, without producing a substantial difference in the shape or contour of the cap when worn. This modification is applicable to the cap shown in Figure 3 by using duplicate props, preferably secured together at the free ends of their respective pairs of legs.

In the modification shown in Figures 8 and 9, the legs 16c and 23c have upright prongs 31 and 32 respectively attached at the ends 19b and 24b. These prongs are substantially the height of the brows of the cap and may terminate in beaks 33, 34 at their upper ends. Here 35 also, when the legs 16c, 23c are contracted to fit into the headband of the cap the chine 13b is bowed as shown in Figure 8. The chine portion may be made considerably shorter than the crest line of the cap, and the beaks 33, 34 are free to enter the points 21, 18 of the 40 cap where they are held by the resiliency of the prongs 31, 32. This construction has the advantage that a single prop may be made to fit a group of cap sizes by making the chine 13b short enough to fit into the smallest cap of the group, and the positioning of prongs 31, 32 supports the points of the cap and the brows. In this modification the prongs 31, 32 may apply tension at the points 21, 18 and the prongs 31, 32 can be adjusted as desired to change or avoid tension without affecting the curvature of the chine.

It will be understood that while we have shown the prop member held in the cap in the sweatband, the prop may be removably anchored in the cap in any other desired manner, or it may be permanently inserted in the cap in any suitable way.

We claim as our invention:

1. In a cap construction of the overseas type comprising side panels of pliable material having arcuate upper edges, said side panels being united at their upper edges to form a curved crest and being united at their front and rear edges to form front and rear brows, the combination of 60 a prop member of spring material, said prop member consisting of a middle chine portion and legs depending from the opposite ends of said chine portion, said chine portion being of a length at least as long as said crest, said legs being in a common plane and normally diverging outwardly and downwardly from said chine portion and of a length conforming substantially to the height of said brows, said chine portion being disposed adjacent said crest, and said brows engaging and compressing said 65 opposed legs to bow said chine portion into tensioning engagement with said crest.

2. A combination, as defined in claim 1, including a second prop member identical with said first-named prop member and coextensive therewith, and means connecting 70 the distal ends of said prop members to each other.

3. A combination, as defined in claim 1, including an extension provided on each of said legs, said extensions extending upwardly from said legs into engagement with the apices of said prows.

4. A combination, as defined in claim 1, in which said legs include bent portions adjacent the juncture of said legs with said chine portion, said bent portions being disposed substantially at right angles to said chine portion when said chine portion is in unbowed condition.

5. A prop member of the character described made of 10 spring material and consisting of a middle chine portion and divergent supporting elements depending outwardly from the opposite ends of said chine portion, each of said supporting elements including a bent portion thereof which extends at substantially a right angle to said chine 15 portion when said chine portion is in unstressed condition.

6. A prop member, as defined in claim 5, wherein said bent portion defines the juncture between said chine portion and said supporting element.

7. A prop member, as defined in claim 5, wherein said bent portion defines the distal end of said supporting element.
